(57) **CLAIM**

The ornamental design for an intercommunication apparatus, as shown and described.

DESCRIPTION

FIG. 1 is a perspective view of an intercommunication apparatus showing our new design;

FIG. 2 is a front view of thereof;

FIG. 3 is a left side view thereof;

FIG. 4 is a right side view thereof;

FIG. 5 is a bottom view thereof;

FIG. 6 is a rear view thereof; and,

FIG. 7 is a top view thereof.

The broken lines shown in the drawings represent portions of the intercommunication apparatus that form no part of the claimed design.
